WEATHER STRIP INSTALLER'S GAUGE

Elmer D. Barringer, Cleveland Heights, Ohio

Application January 13, 1941, Serial No. 374,281

3 Claims. (Cl. 33—180)

This invention has relation to the art of weatherstrip equipment for windows, doors, or the like, and deals primarily with the technique of the fitting of the sash in the runway or runways of window frames, and particularly where so-called rib weatherstrip is to be applied to the window frame for cooperation with the sash.

As is well known, when rib weatherstrips are mounted in the runways of window frames for coaction with the sash, the sash is formed with a groove to receive the rib or rib member of the weatherstrip. The weatherstrip usually comprises a plain or corrugated plate formed with an offstanding rib parallel to the plane of the sash which rib is designed to enter the sash groove and thus provide the means for preventing passage of water, dust, or foreign matter from the outside to the inside of the window.

Heretofore in dealing with the problem of fitting sash to window frames where rib weatherstrips have been employed, the technique of locating the groove in the sash in proper relation to the runway of the window frame and in proper relation to the location of the rib of the weatherstrip has been a somewhat haphazard procedure. So far as I am aware, no accurate method of gauging the relative locations of the groove in the sash and the rib of the weatherstrip, especially in relation to the proper positioning of the weatherstrip with its rib arranged so that the groove in the sash will be accurately centered with adequate clearness, has been developed heretofore.

It is one of the purposes of my invention to devise gauge means so designed as to cooperate with the tool by which the groove is accurately formed and located in the sash to ensure that upon the proper application of the weatherstrip to the runway of the window, the rib will coact properly with the groove in the sash for weatherstrip purposes.

This proper coaction between the rib of the weatherstrip and the sash that slides relative thereto, involves the necessity of an accurate measuring of the location of the groove in the sash from at least one side of the sash so that the rib of the weatherstrip when working in the groove of the sash will enable free movement of the sash as it slides relative thereto, without binding at the time of installation in the first place, and without liability of binding such as might arise later because of the swelling and shrinking of the sash and runway in which runway the sash operates.

In following the method of gauging of my invention and using the gauge equipment herein-after more fully described, I provide a gauge plate with gauge means thereon, by which to determine with extreme accuracy the proper location of the cutting or grooving member of the cutting tool that the installer uses for forming and locating the grooving in the sash, said groove to later receive the rib of the weatherstrip.

10 The problem of gauging as dealt with in my invention involves further the matter of accurate and precise location of the weatherstrip having the rib that is to enter the groove in the sash. My gauging means or special form of gauge plate of my invention deals with this problem by the provision of gauge means capable of being used by the installer, separate from the gauge means previously referred to that deals with the proper location of the cutting element of the cutting tool, for checking the accuracy of formation and location of the groove that is made in the sash by the cutting tool.

20 So far as I am advised, no double method of gauging with the relation to gauging the location of the tool or cutting element used to form the groove in the sash, and checking by gauge means the location of the groove in the sash as made by the cutting element of the tool, has heretofore been proposed.

25 30 The gauge means of my invention has a third function, namely, that by which it is enabled to check the proper location of the rib strip in its runway to ensure that the rib of the strip is in proper alignment with the groove in the sash, and by so doing, correspondingly ensure the proper clearance of the rib relatively to the walls of the groove and the proper clearance between the edge of the sash and the window stop making certain the free movement of the sash in its runway with the rib interlocked in the groove, when the installation is completed.

35 40 A more full understanding of the invention will be had upon reference to the accompanying detail description and to the annexed drawings, in which:

45 50 Figure 1 illustrates a conventional type of window frame equipped with sashes and rib weatherstrips that are dealt with in the formation of the grooves of the sashes and the location of the weatherstrips by the gauging means of this invention.

55 Figure 2 is a fragmentary view of a window frame showing rib weatherstrips therein and illustrating a mode of gauging of checking the proper location of the weatherstrip with its rib

accurately and precisely in the runway in relation to the adjacent stop.

Figure 3 is a fragmentary view of an ordinary type of groove forming cutting tool or grooving plane such as used by weatherstrip installers illustrating the way in which the gauge means of my gauge plate is employed for the accurate adjustment of the position of the cutting bit or member in reference to the so-called fence or side guide of the tool.

Figure 4 is a view that corresponds somewhat with Figure 3, excepting that the gauge means of my invention is adjusted as when used in conjunction with the rotary cutting bit of a common type of rotary or motor grooving tool, usually called a motor groover.

Figure 5 is a perspective view somewhat fragmentary in its nature to illustrate the manner in which the members of my gauge are employed to check the location of the groove formed by the cutting tools as regards the disposition of said groove accurately and precisely as it is formed in the sash.

By referring to Figure 1 of the drawings and the weatherstrip equipment, window frame, and sash illustrated therein, it is notable that the frame is generally designated 1 and the upper sash 2 and the lower sash 3. The sashes slide in runways of the frame, as usual, the sash 2 between the outer stop 4 and the parting strip or stop 5, while the sash 3 operates in its lower runway between the parting strip or stop 5 and the window stop 6.

The gauging means of my invention is intended to ensure accurate location and formation of the groove 7 in each sash which groove receives the rib 8 of the weatherstrip 9 and the accurate positioning of the weatherstrip 9 in the runway in which it is mounted so that its rib will be properly and truly positioned in the groove 7 of the sash in which it operates in order to prevent the difficulties that have been involved heretofore due to inaccuracy of the locations of the said parts as above described.

Dealing with a concrete example of sash construction such as shown in Figure 1, and noting that the window frame 1 is equipped with runways, as customary, say of a width of one-and-three-eighths inches (1 $\frac{3}{8}$), it is highly essential and desirable that the sash shall operate in the runway so as to afford a spacing of the sides of the sash from the stops that guide it in its movement of a predetermined extent or with a predetermined amount of clearance space.

In the example illustrated, this space may preferably be approximately one-thirty-second ($\frac{1}{32}$) of an inch. Now the gauging means of my invention is intended to ensure that one side of the sash shall always be spaced substantially one-thirty-second ($\frac{1}{32}$) of an inch, according to the example above given, from the side of the stop adjacent thereto. Additionally, the desired and accurate completion of installation that is obtainable with my gauge means calls for a positioning of the rib 8 of the weatherstrip 9 with its opposite sides very slightly spaced approximately one-sixty-fourth ($\frac{1}{64}$) of an inch from the adjacent walls of the groove. In other words, the groove 7 will be formed in the actual installation work about one-thirty-second ($\frac{1}{32}$) of an inch wider than the widest portion of the rib 8.

If the above conditions are observed as to the installing location of the groove 7 and disposition of the rib 8 with the stated clearance between one side of the sash and the adjacent side of

the stop, it will be evident that a normal predetermined clearance will always be maintained between the sash and the stops of the frame subject only to slight variation by reason of the swelling or shrinkage of the sash or window frame. However, it will be evident from the illustration and foregoing description, that the sash 2 or 3 under all conditions in its cooperation with the rib of the weatherstrip will never be permitted to rattle when the grooving of the sash and the locating of the weatherstrip ribs is effected by my gauge means because the lateral movement of the sash 2 or 3 as limited by the rib 7 of the weatherstrip can never be greater than one-sixty-fourth ($\frac{1}{64}$) of an inch either way, and the clearance space between the side of the sash 2 or 3 and the side of the stop adjacent thereto is always, in the example stated, as great as approximately one-thirty-second ($\frac{1}{32}$) of an inch.

By the same token, owing to the clearances afforded as stated, the freedom of movement of the sash in relation to the rib strip, assuming the proper location of the latter, either by the gauge plate means of my present invention, or other gauge means that may be employed, will ensure the freedom of sliding of the sash in its runway under all conditions of service. This is due to the fact that my gauging means prevents any liability of a mis-location or inaccurate forming of the groove in the sash in relation to its proper position for coaction with the rib of the weatherstrip and likewise ensures against any possibility of a misalignment or improper location of the rib of the weatherstrip in the runway of the sash, either of which inaccuracies might result in improper weatherstrip functioning of the weatherstrip means or rattling of the window or other defective operation of the weatherstrip with which those who are versed in the art are very familiar.

Illustrating the utility of the gauging means of my invention, I refer to the construction of the gauge plate A which constitutes said gauging means. This gauge plate A has three gauge functions. It comprises a body formed at one edge thereof with a plow gauge B and groove gauge C. The plow gauge B is employed as shown in Figures 3 and 4, by merely reversing the disposition of the body of the gauge for accurately measuring the distance of the cutting members of cutting tools in relation to the fence or guide means of such tools.

In Figure 3 the gauge B is shown with one edge thereof applied to the fence 10 of the hand cutting tool, and the other edge contacting with the bit or cutting member 11 of said tool so that the latter may be tightened in place at a precise and accurate adjustment to form the groove 7 in either sash 2 or 3, as illustrated in Figure 1.

In Figure 4 the plow gauge member B is illustrated contacting at one edge with the guide 12 of the motor groover type of cutting tool which guide is equivalent to the fence 10. The other edge of the plow gauge member B contacts with the adjacent edge of the grooving cutter or bit 13 of the rotary type and enables correct or precision adjustment of said cutter on its spindle 14.

In Figure 5, the groove gauge member C is shown in the manner of its application to the sash entering the groove 7 and enabling a correct and accurate checking of the formation of this groove and its proper and precise location in the sash such that it will coact completely and

effectively with the rib 8 of the weatherstrip 9 located in the runway of the sash.

Of course, it remains necessary in the gauging method and technique of my invention that the weatherstrip 9 must be located accurately and correctly in the runway of the sash; otherwise, the efficacy of my method and technique would be destroyed for even where the groove 1 is correctly located there remains the definite problem of a precision and correct location of the rib 8 for the full application of the method of my invention to ensure the results which I have described above as establishing ideal and efficient weatherstrip installation.

With the foregoing in mind, therefore, my gauge means comprises a body which is accurate in its width measurement to conform with the corresponding measurement of the runways 15 of the window frame 1. Thus, by equipping the edge of the gauge A opposite the edge equipped with the members B and C with the rib gauge member D and rib gauge slot E, I am enabled to properly locate the weatherstrip 9 in its runway ensuring that the rib 8 thereof will be disposed in accurate alignment with an adjacent stop 5 and accurately spaced in parallel relation from said stop a predetermined distance throughout its length.

The manner of use of the rib gauge member D, as just referred to, is illustrated in Figure 2 wherein the gauge slot E is disposed to receive the rib 8 of a weatherstrip emplaced in the runway and the gauge member D is arranged closely in contact with the adjacent stop 5. Since the rib 8 at its widest point is exactly the width of the slot E, there results necessarily the positioning of the rib 8 in absolutely accurate and precise location that it will ensure the location of the weatherstrip with its rib centralized in the groove 1 of the sash as soon as the latter is placed in position in its runway on the frame 1.

In the example of construction illustrated, therefore, the rib 8 will thus be located so that there is a clearance between its sides and the side walls of the groove 1 amounting to about one-sixty-fourth ($\frac{1}{64}$) of an inch at each side. Of course, in giving the example of dimensions above, the dimensions are slightly relative but the principle of the relations of the said dimensions is exemplified primarily.

From the foregoing, therefore, it will be noted that at one edge the gauge A has special gauge equipment for the functions stated, at its other end it has special gauge equipment for the secondary functions stated, and the body of the gauge performs the third function of conforming in width with the width of the runway so as to gauge the position of the member A properly to enable the gauging action which is depicted in Figure 2.

In respect to the employment of my gauge A as regards the formation of its width corresponding generally with the width of the runway, there may be some slight variation in that the runway may be very slightly greater or smaller in width than the gauge A. If the width of the runway is smaller, the gauge will not enter and this will immediately advise the installer that the width of the sash should be the same amount smaller than is the runway. If the runway is slightly larger in width than the width of the gauge plate, likewise, the installer is immediately advised that the width of the sash must be that much greater than the width of the body of the gauge plate A. In other words, the gauge A,

when used for gauging the width of the sash, involves use of the width of that portion of the gauge designated by arrow dotted line X in Figure 5, while the portion of the gauge as to width used for the runway is that as designated by the arrow dotted line Y in Figure 3.

In regard to the accurate location of the weatherstrip 9 and its rib 8 in the runway, other handy gauge means in a measure functioning similar to the use of the gauge A in Figure 2 may be employed, for which purpose, I have devised a gauge member 16, as seen in Figure 2, comprising preferably the end of a weatherstrip installer's hammer handle. A separate application for patent for this particular gauge device has been filed under Serial No. 374,282, and filing date of January 13, 1941. This application has matured into Patent No. 2,255,307, issued September 9, 1941. This gauge member 16 is formed with a rib gauge slot 17 made by a precision tool such as a milling cutter which slot 17 is positioned accurately in relation to flats 18 at opposite sides of the member 16 so that the gauge member 16 may be caused to be disposed with one of its flats 18 in contact with the stop 5, for instance, while the rib 8 is accurately located in relation to the stop 5 and when this is done, the nail or fastening 19 may be hammered in place to ensure that the rib 8 is properly positioned to enter the groove of the sash. Of course, the gauge member 16 can be adjusted to the rib 8 at different points in the length of the rib to ensure the accuracy of the position of the latter in parallelism with the stop 5 or whatever stop is to be accurately spaced from the rib depending upon which runway of the sash is to receive the weatherstrip.

Obviously, since the gauge member 16 is preferably a part of the installer's hammer, by which he nails the weatherstrips in position, said gauge member 16 will be generally used by the installer to a greater extent than the rib gauge D and gauge slot E of my gauge A. The latter will be primarily employed for checking since the gauge A is made of metal not susceptible of any material wear, whilst usually the gauge 16 will be made of wood and ultimately might become slightly inaccurate. My gauge A, as regards the employment of the gauge means D and E checks the location of the rib 8 at opposite sides of the gauge and in relation to both sides of the runway, whereas the gauge 16 only deals with gauging the distance of the rib from one side of the runway.

Having thus described my invention, what I claim as new and desire to secure by Letters Patent of the United States, is:

1. In gauge means for weatherstrip installation upon windows, doors, or the like, a gauge device comprising a body provided at one edge with a tool bit or plow gauge member and formed at said edge spaced from said plow gauge member with a groove gauge member shaped to fit in the groove formed by the tool bit or plow, said plow gauge member having a surface shaped to contact an edge surface of the window sash or like member, said surface located on plow gauge member nearest the groove gauge member to gauge the position of the groove when the groove gauge member is positioned therein the distance between the inner side of the plow gauge member and the more remote edge of the body being substantially equal to the thickness of a standard window sash or like member.

2. In gauge means for weatherstrip installation upon windows, doors, or the like, a gauge device comprising a body provided at one edge

with a tool bit or plow gauge member and formed at said edge spaced from said plow gauge member with a groove gauge member, the opposite edge of said gauge body being formed with a rib gauge slot of substantially the same width as said groove gauge member and a stop engaging gauge member at one side of the slot, said stop engaging gauge member being of substantially the same width as the plow gauge member, the distance between the inner side of the plow gauge member which is shaped to contact and extend over an edge surface of a window sash or like member and the remote edge of the body being of substantially the same width as the thickness of a standard window sash or the like, and the distance from the outer side of the stop engaging gauge member and the more remote edge of the body being of substantially the same

width and shaped to be inserted in a standard runway or the like of a frame in which the sash or the like is fitted, the aforesaid two distances being thereby substantially equal.

5 3. In gauge means for weatherstrip installations upon windows, doors, or the like, a gauge device comprising a body formed at one edge with a rib receiving gauge slot and a stop engaging gauge member at one side of the slot, the edge in which the gauge slot and gauge member are formed being of substantially the same width and shaped to be inserted in the runway or the like opening in the frame in which the window sash or the like is received and determine the position of the rib of the weatherstrip therein.

ELMER D. BARRINGER.
